UNITED STATES PATENT OFFICE.

SVEND BARFOED, OF BERKELEY, CALIFORNIA.

ELECTRIC FURNACE.

1,336,939.

Specification of Letters Patent. Patented Apr. 13, 1920.

Application filed September 25, 1916. Serial No. 121,987.

To all whom it may concern:

Be it known that I, SVEND BARFOED, a subject of the King of Denmark, residing at Berkeley, in the county of Alameda and 5 State of California, have invented new and useful Improvements in Electric Furnaces, of which the following is a specification.

This invention relates to an electric furnace for fixing nitrogen from air, and particularly to improvements on the furnace shown in my co-pending application entitled Electric furnace for fixing nitrogen from air, filed January 19, 1916, Serial No. 72,939.

15 The problem involved in the fixation of atmospheric nitrogen, that is the combination of nitrogen and oxygen in a stable form, is the production of sufficient heat to cause the combination, and thereafter a 20 rapid cooling of the combined products to cause a permanent fixation.

To accomplish this result, various forms of electric furnaces have been employed, many of which have been commercial failures due mostly to structural faults, lack of 25 facilities for continuous operation, and a lack of proper arrangement of cooling and heating mediums.

The object of the present invention is to 30 overcome these difficulties and particularly to provide a novel form of water-jacketed furnace.

Another object of the invention is to provide an electrode of special construction and 35 in conjunction therewith, means for evenly distributing the incoming air, and simultaneously cooling said electrode.

Further objects will hereinafter appear.

The invention consists of the parts and 40 the construction and combination of parts as hereinafter more fully described and claimed, having reference to the accompanying drawing in which:—

Figure 1 is a central vertical longitudinal 45 section of the furnace.

Fig. 2 is an enlarged cross section of the lower electrode.

Fig. 3 is a plan view of same.

Fig. 4 is an enlarged detail section on 50 line 4—4 of Fig. 3.

Fig. 5 is a view similar to Fig. 2 showing another form of the lower electrode.

Referring to the drawings in detail, A indicates the furnace proper. In this instance consisting of a water-jacketed tube 2 55 into which projects a pair of electrodes 3

and 4. The electrode 3 is preferably solid and constructed of copper, steel, or any other metal desired, while the lower electrode consists of a refractory cup 5 which is filled with metallic oxid such as indicated 60 at 6 as will hereinafter be described.

The upper electrode is preferably made in sections which are adapted to be joined together by a connection similar to the one indicated at 7, and means have furthermore been provided for rotating said electrode and simultaneously forcing it into the furnace chamber 8 at a rate which is just sufficient to maintain a fixed space between the 70 electrodes, as burning away or consumption of the same takes place. The mechanism for rotating and feeding the upper electrode into the furnace chamber is a duplication of that shown in my co-pending application 75 and briefly speaking, consists of two sets of driven gears, such as indicated at 9 and 10. The gear train 10 being provided for the purpose of rotating the electrode and the gear train 9 for feeding the electrode into 80 the furnace as consumption takes place.

Centrally disposed with relation to the furnace chamber 8 is a gas cooler generally indicated at B. This cooler together with the tubular casing forming the furnace 85 chamber 8, is insulated from the lower electrode 4 by a fiber or asbestos plate 16, secured between flanges 17 and 18 as shown. The upper electrode 3 passing through the center of the cooler is therefore insulated 90 from the lower electrode 4, and as this is in turn insulated from the furnace chamber, it can readily be seen that an arc will be formed between the electrodes.

The gas cooler employed in the present 95 instance is cup shaped and in general appearance a duplicate of the cooler shown in my co-pending application. It is provided with an annular discharge passage 19 which communicates with the furnace chamber 8, and is completely surrounded by a water jacket on both sides, a constant circulation in said jackets being maintained through pipes 22 and 23 which are connected with a source of water supply by means of 100 a pipe 21.

Centrally disposed in the lower portion of the cooler B and projecting into the upper end of the furnace chamber or the lower end of the annular discharge passage 19, is 110 a water-jacketed tube 24 through which the electrode 3 passes. This tube is provided

for the purpose of guiding the electrode 3 and also for the purpose of cooling same. Pipes 25 and 26 connected with the main pipe 21 and the return pipe 21^a provides a 5 means for maintaining a constant circulation in the tube. The tube is furthermore provided with a stuffing box 27 at its upper end which positively prevents any escape of gases between the electrode and the tube 24. 10 The shape and construction of the furnace chamber together with the construction of the lower electrode and means for admitting air to the furnace, constitute the main subject matter of the present invention.

15 Secured by bolts 30 to the lower flange 17 of the furnace is a cone shaped casing 31 which forms a support for the lower electrode. This electrode is supported on a disk shaped cast iron plate 32 which in turn is 20 supported upon a pipe 33 extending through a stuffing box 34 formed in the lower casing, and connected with a source of air supply such as a blower or compressor not here shown. The disk 32 is cored out to form 25 a plurality of radially disposed air passages 35 which communicate with an annular discharge opening 36 formed in the periphery of the disk 32. Suitably secured on top of the disk is an insulating ring 37 and secured 30 upon the said ring in any simple manner is the refractory cup 5 which serves as a container for the metallic oxid of which the electrode is constructed.

It is known that certain gaseous chemical 35 compounds such as oxids of nitrogen are formed by passing air through or into immediate contact with an electric arc. Many attempts have been made to produce compounds of this nature such as nitric acid, etc., 40 on a commercial scale, but these attempts have proven more or less unsuccessful for the following reasons:

No furnace has seemingly been produced 45 which is capable of continuous operation, nor has any furnace been produced in which the air or gases heated to a high temperature by the arc, is sufficiently rapidly cooled to permit fixation of the combined products. It is known that the gaseous 50 chemical compounds formed at high temperatures easily decompose if they are not rapidly cooled from the high temperature at which they are formed, to a comparatively low temperature.

55 The former cooler shown in my co-pending application and also in the present application has positively solved the problem of rapidly cooling the air after it leaves the arc, while minor mechanical difficulties such 60 as cooling of the lower electrode and the interior wall of the furnace, have been overcome by the construction shown in the present case.

In operation when an arc is formed between the electrodes, it is only necessary to

admit the air from the blower or compressor under comparatively high pressure to the furnace chamber through the pipe 33 and the annular discharge passage 36 formed in the base of the lower electrode. The air admitted through the pipe 33 passes through the radially disposed passages 35 then up through the annular passage where it is deflected inwardly against the exterior face of the cup containing the metallic oxid. 75 This manner of admitting the air is of great importance as it cools the electrode to such an extent that boiling over of any molten material is positively prevented. The air after striking the exterior surface of the cup 80 continues in an upward direction along the water cooled wall of the furnace chamber, and will consequently during its passage be brought into such intimate contact with the arc that the gaseous chemical compounds 85 are formed. These compounds are however easily decomposed if they are not rapidly cooled from the high temperature at which they are formed to a comparatively low temperature. This is overcome by the present arrangement as the large cooling area 90 provided by the annular passage 19 permits such rapid cooling that comparatively little decomposition can take place.

By referring to Figs. 2 and 3 it will be 95 seen that a plurality of angularly disposed vanes 40 have been formed in the annular discharge passage 36. This serves the function of deflecting the air or imparting a swirling movement to same which causes it 100 to ascend upwardly along the walls of the furnace chamber in a comparatively solid column. These vanes are of considerable importance as their function is not only one of producing a swirling movement, but also 105 causes a more uniform heating and exposure of all the air passed through the furnace.

The vanes are of further importance as the centrifugal action produced by the swirling movement of the ascending air column 110 permits the inner layer of air to be acted on by the arc while the outer layer serves as a cooling layer or insulation between the arc and the metal surface of the furnace. Similarly the heating of the inner layer causes 115 an expansion of same and a circulation which permits it to contact with the outer chilled layer of air, thus permitting a permanent fixation to take place when mixing of the two air layers takes place. The whole 120 air volume being of course cooled to a desirable degree by passing through the annular passage 19 as previously described.

For the purpose of permitting an even burning of the electrodes, a continuous rotation is imparted to the upper electrode by means of the gear train 10. The lower electrode 4 will however remain stationary and would therefore have a tendency to burn unevenly unless means for swinging the arc is 130

empicyed. This is accomplished by closing a portion of the annular discharge passage 36 by covered plate 50 or the like. The provision of this cover plate prevents any air 5 from discharging between the vanes at this point of the annular discharge passage, and consequently causes an unbalancing of the ascending air column. Such unbalancing causes the arc to swing in a circle around 10 the lower electrode, the radius of the swinging movement depending entirely upon the degree of unbalancing produced, this being in turn regulated by increasing or decreasing the size of the covering plate 50. An 15 even burning of both the electrodes is in this manner obtained without resorting to any mechanical movement as far as the lower electrode is concerned, in fact it has been found in actual practice that rotation of the 20 upper electrode may also be eliminated in this instance as the unbalancing of the ascending air column will cause the arc to swing in a circle over both faces of the electrodes.

25 The electrode shown in Fig. 5 is substantially the same as that shown in Fig. 2, the only difference being that the metallic oxid is entirely supported within a refractory cup 45, through the bottom portion of which 30 extends a plurality of metallic pins 46 which are provided for the purpose of establishing a circuit through the cup.

Another feature provided in connection with this form of electrode is the annular 35 groove 47, which serves the function of collecting any metallic oxid which might have a tendency to boil over.

The materials and finish of the several 40 parts of the device may otherwise be such as the experience and judgment of the manufacturer may dictate.

I wish it understood that various changes in form, proportions and minor details of 45 construction may be resorted to within the scope of the appended claims, and that I do not wish to limit myself to the specific design or construction here shown.

Having thus described my invention, what I claim and desire to secure by Letters Patent is:—

50 1. An electric furnace comprising an elongated water-jacketed tube, an electrode in each end of the tube, means for admitting air or gas at one end of the tube and directing 55 it through the sphere of action of the electric arc, and means forming a continuation of the other end of the tube for rapidly decreasing the temperature of the air or gas after it leaves the electric arc.

60 2. An electric furnace comprising an elongated water-jacketed tube, an electrode in each end of the tube, means for admitting air or gas through an annular air passage formed at one end of the tube around one of the electrodes and directing it through the sphere of action of the electric arc, means for imparting a swirling movement to the air during its passage through the tube, and means forming a continuation of the other end of the tube for rapidly decreasing the temperature of the air or gas after it leaves the electric arc.

65 3. The combination with an electric furnace, of an electrode mounted in one end of the furnace, said electrode comprising a hollow base member having an air intake opening formed therein and an annular discharge passage and a cup shaped member on said base surrounded by the annular discharge passage and adapted to be cooled by the discharging air.

70 4. The combination with an electric furnace, of an electrode mounted in one end of the furnace, said electrode comprising a hollow base member having an air intake opening formed therein and an annular discharge passage, a cup shaped member on said base surrounded by the annular discharge passage and adapted to be cooled by the discharging air, and deflecting members in the annular discharge passage adapted to impart a swirling movement to the air as it leaves said passage.

75 5. The combination with an electric furnace, of an electrode mounted in one end of the furnace, said electrode comprising a hollow base member having a central air intake opening formed therein and an annular discharge passage, a pipe connected at one end with the central intake opening and at the other end with a source of air pressure supply, and a cup shaped member on said base surrounded by the annular discharge passage adapted to be cooled on its exterior surface by the discharging air, said cup serving as a container for a metallic oxid.

80 6. The combination with an electric furnace and the electrodes mounted therein, of means for rotating one of the electrodes to continuously change the position of the arc between the electrodes to permit an even burning of same.

85 In testimony whereof I have hereunto set my hand in the presence of two subscribing witnesses.

SVEND BARFOED.
